UNITED STATES PATENT OFFICE.

MATTHIAS BROCK, OF BOSTON, MASSACHUSETTS, ASSIGNOR TO THE MCKAY & COPELAND LASTING MACHINE COMPANY, OF PORTLAND, MAINE.

MACHINE FOR DRIVING HEADED FASTENINGS.

SPECIFICATION forming part of Letters Patent No. 442,418, dated December 9, 1890.

Application filed August 28, 1890. Serial No. 363,280. (No model.)

To all whom it may concern:

Be it known that I, MATTHIAS BROCK, of Boston, county of Suffolk, State of Massachusetts, have invented an Improvement in Machines for Driving Headed Fastenings, of which the following description, in connection with the accompanying drawings, is a specification, like letters and figures on the drawings representing like parts.

10 This invention has for its object to improve and simplify that class of machines adapted to drive headed tacks, my invention being more especially adapted to drive tacks into tack-strips.

15 In accordance with my invention the tacks are fed automatically into a raceway, down which they travel to a supporting-plate, and thereafter the raceway has imparted to it a slight lateral vibration to thus cut off or de-
20 tach from it the endmost tack, and a pusher then acts on the tack so cut off and pushes it laterally into position to be struck by the driver, the supporting-plate being drawn out from under the head of the tack just before
25 the pusher engages the tack and after the raceway has been swung aside, as stated.

The particular features in which my invention consists will be described in the following specification, and designated in the claims
30 at the end thereof.

Figure 1 is a front elevation of a tack-driving machine embodying my invention; Fig. 2, a detail showing the raceway in plan view together with the supporting-plate and pusher; Fig. 3, a plan view of the machine shown in Fig. 1; Fig. 4, an enlarged partial longitudinal section of the machine in the line of the center of the raceway; Fig. 5, an enlarged section in the line x , Fig. 2. Fig. 6 is a section
35 to the left of the line x' , Fig. 3. Fig. 7 is an enlarged detail showing the stationary throat located at the lower end of the raceway and on which the supporting-plate slides and in which the pusher slides; and Figs. 8, 9, and
40 10 are details showing the end of the raceway and the supporting plate and pusher in different positions.

The frame-work A of the machine is and may be of suitable shape to sustain the sup-
50 porting parts. The main shaft a^1 has loose

on it the clutch-pulley F' under the control of a lever f^5 , having connected to it a slide-rod F. The said shaft has fast on it a grooved hub c^7 , the end of which next the loose pulley F' (see Fig. 6) is notched to be engaged by 55 projections of corresponding shape on the hub of the said loose pulley when the shaft a^1 is to be rotated. The hub c^7 actuates a rock-shaft d^12 , having at its lower end an arm d^11 , which in practice will actuate the feeding 6c devices, as in United States Patent No. 247,143. The shaft a^1 also carries a grooved hub c^6 , which actuates a lever c^4 , which reciprocates a pusher-slide c^2 . The drive-rod C is attached to a drive-bar c^12 , which is actuated by the disk c^11 . The tack-receiving hopper is marked a, it containing a tack-lifting wheel and a wiper or clearing device a^9 to dislodge from the raceway any tacks improp-
65 erly lodged thereon.

All the parts thus far specifically referred to and designated by letters are substantially the same as in the Patent No. 247,143.

The wiper a^9 is fast on the end of a short shaft, (not shown,) supported in bearings in 75 the hopper, the other end of the said shaft having fast on it a pinion a^2 , which derives its motion from a pinion a^3 and intermediate gears a^4 a^5 , the pinion a^3 being fast on a shaft a^6 , having a bevel-gear a^7 , which is engaged 80 and rotated by a bevel-gear a^8 , fast on the main shaft a^1 .

The raceway B has at its upper end deflecting-aprons B', on which the wheel B² in the hopper drops the tacks lifted by it. This 85 raceway, as best shown in Figs. 2 and 3, is pivoted at b^3 , (see dotted lines, Fig. 3,) and is vibrated at proper times by a link B⁴, preferably made adjustable as to its length, which is joined to the upright lever B⁵, pivoted at 90 B⁶, and having a roller or other stud B⁷, which enters a cam-groove in the cam-hub B⁸, fast on shaft a^1 . The raceway is "tapped" or jarred by the lever C⁹, acted upon by a lug 2 of the disk or hub C' on shaft a^1 , a spring 95 3 operating the lever in opposition to the said lug. The raceway has a cap 4, which prevents the tacks properly suspended in the raceway from escaping. The lower end of the raceway rests upon a stand 6, made ad- 100

justable on a throat-block D by a screw 7. The delivery end of the raceway has a horizontal notch 8, which is entered by the crowding-back finger 10, attached to the throat-block 5 when the raceway is moved laterally from the position in Fig. 8 to that in Figs. 9 and 10, the said finger at such time acting against the tack next to the endmost one and pushing back in the raceway all the tacks except 10 the one marked 12, (see Figs. 8 and 9;) which tack during the lateral movement of the raceway is picked off from the raceway by a picker 13, (shown as a stationary prong forming part of the throat-block.) The tack 15 12, picked off by the picker 13, enters a notch in a supporting-plate e, which is reciprocated for a short distance on the throat-block toward and from the end of the raceway by a cam-finger 14 and a spring 15, the said cam-finger being connected to the pusher-slide c² and acting on a roller-stud 16 on the plate e. The pusher-slide c² has attached to it the pusher m, which moves in the slot m' (see Fig. 7) of the throat-block at right angles to 20 the supporting-plate and raceway, the said slot leading toward and being in communication with the passage-way 17, in which descends or moves the drive-rod C. (Shown in section, Figs. 8 and 9.)

25 30 The slotted end of the plate e embraces loosely a lug e', (see Figs. 7 and 8,) against which the tack to be detached or picked off from the raceway abuts as a stop, the prongs of the supporting-plate at such time, as in Fig. 8, extending beyond the face of said lug, but as the raceway is moved from the position Fig. 8 into the position Fig. 9 the said plate is retracted and its prongs are drawn back of the face of the lug, so that as the 35 40 pusher m meets the tack 12 it may push it from between the said lug, past the left-hand side of the prong 13, and along the slot m' toward the end of the said slot and next the drive-rod C, which is then down, as in Fig. 45 50 9, the raceway at such time being swung about its pivot into the position, Fig. 9, it remaining in such position until the drive-bar descends on the tack 12, (see Fig. 10,) and drives it, the drive-bar being lifted out as the 55 60 tack 12 is brought to the passage-way 17.

The tack 12 is put into the passage-way 17 directly under the drive-rod as the latter is elevated above the passage 17. The passage-way 17 has slots at each side to receive 65 70 75 jaws 20, acted upon by springs c⁸, (See Fig. 1,) the said jaws and springs being common to the patent referred to and acting to keep the tack in vertical position while being driven by the drive-rod.

80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950 955 960 965 970 975 980 985 990 995 998 1000

24 at the delivery end of the raceway is longer than the other prong alongside of it, said prong being at the level of the prongs of 70 the supporting-plate, as in Fig. 4, so that the tack detached from the raceway will rest on the said plate. Viewing Fig. 8, it will be seen that the head of the tack 12 next to be carried away by the pusher rests on the stop e' 75 and on both prongs of the plate e, the tack-head being thus supported on three sides. Now as the raceway is swung aside into the position Fig. 9 and the plate e is withdrawn the prong 24 of the raceway comes under the 80 head of the tack and supports it at its side opposite the stop e', the head of the tack yet remaining on the said stop. This is shown in Fig. 9. The raceway-prong 24 remains in the position Fig. 9 until after the pusher m 85 strikes the rear side of the tack 12, and when the pusher places the tack in the passage 17 and retires the raceway is turned back into its normal position. The plate e is shown as attached by screws 28 to a plate-carrier slide 90 e¹⁰, in which is an adjusting-screw by which to control the forward position of the plate e.

The throat-block D has a cap-piece 30, attached to it by suitable screws in the threaded holes 31. 95

The term "tack" is considered to comprehend any headed nail or fastening.

It will be noticed in my improved machine that the raceway is vibrated laterally and that the pick-off is stationary, which so far as I am aware is novel.

Prior to my invention it has been common to employ a movable pick-off at the end of a stationary roadway.

The plan invented and adopted by me is 105 simpler and more durable than older forms known to me.

This invention is not limited to the exact form of means for moving it laterally back and forth with relation to the plate e.

I do not claim a longitudinally-reciprocating raceway.

Referring to Figs. 1 and 6, n and n' represent arms attached to a rock-shaft. The arm n' is slotted to embrace a pin n² on a slide n³. 115 This slide is adapted to co-operate with certain feelers described in a former patent granted to me, and need not be herein specifically described.

I claim—

1. In a machine for driving headed fastenings, the following instrumentalities, viz: a laterally-movable raceway, a stop located at the end of the raceway to control the flow of tacks, means to move the raceway back and forth laterally, and an independent pick-off, to operate substantially as described.

2. In a machine for driving headed fastenings, the following instrumentalities, viz: a laterally-movable raceway, a stop located at the end of the raceway to control the flow of tacks, means to move the said raceway back and forth laterally, and a crowding-back device, to operate substantially as described.

3. In a machine for driving headed fastenings, the following instrumentalities, viz: a raceway, means to move it back and forth laterally, a stop e' , a pick-off, and a movable supporting-plate having prongs to co-operate with the said stop, substantially as described.

4. The laterally - movable raceway having one of its prongs 24 longer than the other, the stop e' , and the movable supporting-plate notched at its forward end to straddle the said stop, combined with a pusher and a throat-plate having a driver-passage, and a crowding-back device, to operate substantially as described.

15 5. The laterally - movable raceway, the throat-block having the pick-off, the stop e' , and the movable supporting-plate notched to

embrace the said stop, combined with a pusher-slide, the pusher, and the cam-finger 14, to operate substantially as described. 20

6. The laterally - movable raceway, the throat-block having the pick-off, the stop e' , and the movable supporting-plate notched to embrace the said stop, combined with the pusher and with the slide e^{10} , and means to 25 adjust and control the forward position of the same, substantially as described.

In testimony whereof I have signed my name to this specification in the presence of two subscribing witnesses.

MATTHIAS BROCK.

Witnesses:

GEO. W. GREGORY,
EMMA J. BENNETT.
